UNITED STATES PATENT OFFICE

PRINCE A. GARDNER, JR., OF ST. LOUIS, MISSOURI

DESIGN FOR A BILL FOLD

Application filed August 8, 1932. Serial No. 44,549. Term of patent 14 years.

To all whom it may concern:

Be it known that I, PRINCE A. GARDNER, Jr., a citizen of the United States, residing at the city of St. Louis, State of Missouri, have invented a new, original, and ornamental Design for a Billfold, of which the following is a specification, reference being had to the accompanying drawing, forming part thereof.

The figure is a perspective view of a billfold, showing my new design.

The design appears entirely on the side of the billfold shown in the drawing, the opposite side being plain.

I claim:—

The ornamental design for a billfold, as shown and described.

PRINCE A. GARDNER, JR.
